(57) **CLAIM**

The ornamental design for a control board device for machine tool, as shown and described.

DESCRIPTION

FIG. 1 is a front view of a first embodiment of a control board device for machine tool showing our new design;

FIG. 2 is a back view thereof;

FIG. 3 is a top view thereof;

FIG. 4 is a bottom view thereof;

FIG. 5 is a right side view thereof;

FIG. 6 is a left side view thereof;

FIG. 7 is a front view of a second embodiment of a control board device for machine tool showing our new design;

FIG. 8 is a back view thereof;

FIG. 9 is a top view thereof;

FIG. 10 is a bottom view thereof;

FIG. 11 is a right side view thereof; and,

FIG. 12 is a left side view thereof.

The broken lines in the drawings depict environmental subject matter only and form no part of the claimed design.

1 Claim, 12 Drawing Sheets
